CLAIM

The ornamental design for an electronic atomizing device assembly, as shown and described.

DESCRIPTION

FIG. 1 is a perspective view of an electronic atomizing device assembly shown in an assembled configuration of use according to a first embodiment;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the electronic atomizing device assembly shown in FIG. 1, in an opening state;

FIG. 10 is a perspective view of an electronic atomizing device assembly showing a first component removed from the assembly in FIGS. 1-8 for clarity of disclosure;

FIG. 11 is another perspective view thereof;

FIG. 12 is a front elevational view thereof;

FIG. 13 is a rear elevational view thereof;

FIG. 14 is a left side elevational view thereof;

FIG. 15 is a right side elevational view thereof;

FIG. 16 is a top plan view thereof;

FIG. 17 is a bottom plan view thereof;

FIG. 18 is a perspective view of an electronic atomizing device assembly showing a second component removed from the assembly in FIGS. 1-8 for clarity of disclosure;

FIG. 19 is another perspective view thereof;

FIG. 20 is a front elevational view thereof;

FIG. 21 is a rear elevational view thereof;

FIG. 22 is a left side elevational view thereof;

FIG. 23 is a right side elevational view thereof;

FIG. 24 is a top plan view thereof;

(Continued)

FIG. 25 is a bottom plan view thereof;
 FIG. 26 is a perspective view of an electronic atomizing device assembly shown in an assembled configuration of use according to a second embodiment;
 FIG. 27 is another perspective view thereof;
 FIG. 28 is a front elevational view thereof;
 FIG. 29 is a rear elevational view thereof;
 FIG. 30 is a left side elevational view thereof;
 FIG. 31 is a right side elevational view thereof;
 FIG. 32 is a top plan view thereof;
 FIG. 33 is a bottom plan view thereof;
 FIG. 34 is a perspective view of an electronic atomizing device assembly showing a first component removed from the assembly in FIGS. 26-33 for clarity of disclosure;
 FIG. 35 is another perspective view thereof;
 FIG. 36 is a front elevational view thereof;
 FIG. 37 is a rear elevational view thereof;
 FIG. 38 is a left side elevational view thereof;
 FIG. 39 is a right side elevational view thereof;
 FIG. 40 is a top plan view thereof; and,
 FIG. 41 is a bottom plan view thereof.

The broken lines in the drawings depict portions of the electronic atomizing device assembly that form no part of the claimed design.

The shade lines in the figures show contour and not surface ornamentation.

The oblique shade lines in the drawings indicate transparency
